UNITED STATES PATENT OFFICE.

FRANCIS CHADWICK CLARK, OF KANSAS CITY, KANSAS.

SHOE-BRUSH.

1,237,475.

Specification of Letters Patent. Patented Aug. 21, 1917.

Application filed January 31, 1917. Serial No. 145,632.

To all whom it may concern:

Be it known that I, FRANCIS CHADWICK CLARK, a citizen of the United States, residing at Kansas City, in the county of Wyandotte and State of Kansas, have invented 5 certain new and useful Improvements in Shoe-Brushes, of which the following is a specification.

My invention relates to new and useful 10 improvements in shoe brushes, and my object is to provide a simple and complete device of this character incorporating coacting means for holding a box of blacking, means for applying the blacking to shoes, 15 and means for polishing the shoes after the blacking has been applied thereto.

In order that the invention may be fully understood, reference will now be made to the accompanying drawings, in which:

20 Figure 1 is a side elevation of a shoe brush constructed in accordance with the invention.

Fig. 2 is a plan view of the shoe brush.

25 Fig. 3 is a longitudinal section on line III—III of Fig. 2.

Fig. 4 shows the dauber of the brush adjusted in forward position to apply blacking to the shoes.

30 In carrying out the invention, I employ a primary handle 1, provided at its reduced forward portion with a recess 2 to receive a box of blacking A. The underside of said primary handle 1 is covered with a polishing element 3 consisting, preferably, of a 35 thick sheet of felt or other suitable material.

5 designates a supplemental handle, the rear portion of which is adapted to fit into an off-set 6 in the upper portion of the primary handle 1, to which it is operably-connected by links 7 and 8. The forward portion of said supplemental handle 5 has a tubular shaft 9 journaled and slidably mounted therein and provided at its upper end with a knob 10 and at its lower end with 45 a dauber 11, which is normally disposed above the box of blacking as disclosed by Fig. 3.

The knob 10 has a central opening therethrough communicating with the interior of the tubular shaft 9, so that water may be introduced therethrough to the bristles of the dauber 11, to moisten said bristles preparatory to rubbing them over the blacking. One side of the upper portion of the dauber 55 is normally held against a stop 12, on the underside of the supplemental handle 5, by

a coil spring 13 secured at its upper end to the tubular shaft 9 and at its lower end to a side wall of a recess 14 formed in the top of the supplemental handle 5 to receive said 60 spring 13.

16 designates a cover to close the top of the blacking box A to exclude dust therefrom and prevent the blacking from drying out when the brush is not in use. Said cover 65 has two depending flanges 17, which snugly fit opposite sides of the forward portion of the primary handle 1 and thus hold the cover plate in place. It is also provided with an upturned handle 18 whereby it may 70 be grasped preparatory to removing it or applying it to the handle 1.

When it is desired to use the brush, the cover 16 is removed and water is introduced to the bristles of the dauber 11 through the 75 knob 10 and the tubular shaft 9. After thus moistening the bristles of the dauber, the knob 10 is rotated about a half revolution to the right and at the same time pressed downwardly to cause the bristles of the 80 dauber to rub over the blacking in the box A. After the dauber has been thus coated with the blacking, the knob 10 is released, whereupon it is pushed upwardly and rotated backwardly to normal position against 85 the stop 12, by the spring 13. The supplemental handle 5 is then adjusted forwardly to the position disclosed by Fig. 4, so that the dauber 11 with its coating of blacking 90 can be rubbed over the shoes. After the blacking has been applied to the shoes, the supplemental handle 5 is adjusted backwardly to its normal position, Fig. 1, to coact with the primary handle 1 in affording a 95 convenient grip to the user who then proceeds to polish his shoes by rubbing the polishing element 3 thereover.

From the foregoing description, it is apparent that I have produced a shoe brush embodying all of the features of advantage 100 above enumerated, and while I have shown and described the preferred form of invention, I reserve the right to make such changes in the construction, combination, and arrangement of parts as properly fall 105 within the spirit and scope of the claims.

Having thus described my invention, what I claim and desire to secure by Letters Patent, is:

1. In a device of the character described, 110 a primary handle having two offsets in its upper portion, said primary handle having

a recess to hold a box of blacking, a dauber adapted to be rubbed over the surface of said blacking, and a supplemental handle carrying the dauber and operably-connected 5 to the primary handle to move into position in either of the offsets therein and affording a gripping surface in all positions thereof.

2. In a device of the character described, a primary handle having a recess to receive 10 a box of blacking in one end thereof, an offset above the recess terminating in a shoulder at the opposite end of the primary handle, a shiftable supplemental handle for seating on said offset and having its movement restricted by engagement of one end thereof with said shoulder, a dauber carried by the opposite end of said supplemental handle, and links connected at their ends to the two handles and extending across the 15 joints therebetween to guide and limit the movement of the supplemental handle away from said shoulder.

3. In a device of the character described, a primary handle having a cut-out in its 25 upper face terminating at one end in a shoulder and having a blacking box receiving part in front of the other end of the cut-out, a shiftable supplemental handle received in said cut-out and having one end 30 engageable with the shoulder to limit the movement of the supplemental handle in one direction, means for guiding and limiting the movement of the supplemental handle in the opposite direction, and a dauber 35 carried by the supplemental handle and engageable with the blacking.

4. In a device of the type set forth, a block forming a primary handle having a cut-out in its upper face terminating at 40 one end in a shoulder and having a blacking-box receiving recess below the plane of the cut-out, a shiftable supplemental handle in said cut-out and having one end engage-

able with the shoulder, said supplemental handle having its top and sides substantially 45 registering with and forming continuations of the top and sides respectively of the primary handle and having its opposite end extending substantially flush with the end of the primary handle adjacent the blacking box recess, and a dauber carried by said opposite end of the supplemental handle.

5. In a device of the type set forth, a primary handle, a shiftable supplemental handle thereon, said primary handle having 55 a blacking box holding part and said supplemental handle having one end movable over and beyond said part, a dauber carried by said supplemental handle and normally arranged over said box holding part, spring 60 means to normally hold the dauber out of engagement with the blacking, and means to supply water to the blacking through said supplemental handle.

6. In a device of the type set forth, a primary handle, a shiftable supplemental handle, means to guide said supplemental handle, said primary handle being formed with an upper part and a lower part, the latter located in advance of the upper part to 70 enable said supplemental handle to seat on either part, and a dauber, said dauber being connected to the supplemental handle so that when the latter seats on the lower part the dauber will project out from the primary handle and when the supplemental handle seats on the upper part the dauber will be held in superposed relation to said lower part.

In testimony whereof I affix my signature, in the presence of two witnesses.

FRANCIS CHADWICK CLARK.
